ADJUSTABLE LINE WIDTH WRITING
FOUNTAIN PEN

Thomas W. Lepkowski, New York, N. Y.

Application May 6, 1950, Serial No. 160,465

6 Claims. (Cl. 120—42)

1

This invention relates to fountain pens, and more particularly, to a fountain pen including means for adjusting the width and depth of the line produced by its writing point, a novel writing point, and a novel filling mechanism. The present application is, in part, a continuation of my copending application Serial No. 92,322, filed May 10, 1949, for "Adjustable Line Width Writing Fountain Pen and Method of Manufacturing Novel Pen Point Thereof," which has eventuated in U. S. Letters Patent No. 2,567,608.

The fountain pen in accordance with the present invention comprises a member carrying at opposite ends thereof a pen point and an ink sac and filling mechanism therefor connected by an ink passage, which member is mounted within and axially movable with respect to a shell having a barrel at one end, a hood at the other and a selector sleeve intermediate thereof, the pen point, of a resilient metal, being formed so that the writing line produced thereby may be controlled as to the thickness thereof through its co-action with the hood as the member carrying the pen point is axially reciprocated relative to the shell upon actuation of the rotatable sleeve which is operatively associated with said pen point carrying member.

In accordance with the present invention, the pen point may be prepared as outlined in the aforementioned copending application, or alternatively, the same may be produced as follows: The pen point is blanked out flat from a metal sheet of springy material such as stainless steel; a precious metal ball is welded to the writing point thereof, the opposing tapering sides defining the nib divisions thereof are coined to an arcuate conformation at their upper edges; the blank is then bent transversely about a small radius of curvature; the thus-bent blank is slotted through the ball to its pierce hole thereby providing cooperating nib divisions, the juxtaposed edges and, in particular, the slit ball ends of which are in substantial parallelism to one another; the nib divisions are then pressed upwardly conforming to a relatively larger radius of curvature to a predetermined maximum desired degree of separation and angular relationship of the ball portions, in which condition the juxtaposed edges of the nib divisions and the faces of the writing ball portions become slightly transversely spaced and have an inclination to each other forming substantially an inverted V.

The pen point is then secured in the outer end of a substantially tubular, partially threaded member which is non-rotatably mounted for axial

movement in the fountain pen shell consisting of a barrel, a guide nipple, a rotatable selector sleeve and a hood. The inner end of this member has the open end of the ink sac secured thereto, and the member serves to feed ink from the sac to the ink feed plug extending longitudinally therethrough and leading to the pen point at the outer end thereof. The ink sac is embraced by an elongated U-shaped spring whose arms are transversely curved to conform substantially to the curvature and the diameter of the ink sac. One end of this spring is fixed relative to the axially movable member and the other end is free. By removing the separable protective cap from the barrel end, the spring may be depressed to collapse substantially the entire length of the sac to expel air by pinching the same along the arcuate zones at opposite sides thereof, so that the sac is completely filled upon release of the spring.

20 An interiorly frusto-conical cam sleeve defining the nib division adjusting hood surrounds the pen point and has its inner surfaces sloping in the same direction as the slopes or tapers of the arcuately coined outer edges of the nib divisions. However, the slope angle of the cam sleeve surfaces is greater than that of the taper of the nib edges of the pen point; consequently, axial movement of the pen point relative to the cam sleeve either presses the nib divisions and the ball writing surfaces carried at the end thereof toward each other to reduce the transverse spacing and angularity between the juxtaposed surfaces thereof, or releases the nib divisions from compression so that the same, and particularly 25 the juxtaposed surfaces of the ball portions, expand toward the initial maximum separation. As the nib divisions are displaced toward each other, the faces of the writing ball portions assume a lesser angle of divergence and transverse spacing, 30 approaching a parallel, juxtaposed position. This action results in producing a finer writing line of the pen point and the converse is true as the nib divisions, in absence of restraint, return to their normal position of maximum separation. 35 Consequently, relative axial adjustment of the cam sleeve and the pen point varies the width of the writing line.

For a thorough understanding of the invention principles, reference is made to the following detailed description of a typical embodiment thereof as illustrated in the accompanying drawing. In the drawing:

Fig. 1 is an axial sectional view through a fountain pen embodying the invention, illustrat-

ing the writing line width adjustment mechanism in one extreme position;

Fig. 2 is a partial axial sectional view illustrating the adjusting mechanism substantially in the opposite extreme position;

Fig. 3 is a transverse sectional view on the line 3—3 of Fig. 2;

Fig. 4 is an exploded view of the writing line width adjusting mechanism;

Fig. 5 is a perspective view of the pen point blank prior to bending;

Figs. 6 through 8 are elevation views of the nib ends carrying the writing ball sections of the pen point at different adjustments; and

Fig. 9 illustrates an intermediate position of the adjusting mechanism.

Referring to the reference characters in the drawing, and in particular to Figs. 5 to 8 inclusive, the pen point 10 is formed by blanking a flat metal sheet of springy material such as stainless steel and treating the same in succession as follows: First, a flat blank, the sidewalls 19, 19' at the forward portion of which define a taper, has applied to the tapered tip end thereof a ball 80 of precious metal, as by welding. Then, the sidewalls 19, 19' along the taper of the blank are coined to an arcuate conformation 90. The blank is then bent transversely about a small radius of curvature and while so maintained is slit from the tapered end thereof up to the pierced hole or heart 95, thereby providing nib divisions 13, 13' having respectively at their ends ball portions 12, 12', the juxtaposed edges of which are in parallelism to one another; the end conformation of the pen point is attained by pressing the nib divisions thereof upwardly to conform to a relatively larger radius of curvature than that of the initial transverse bending, and thereby defining the predetermined maximum degree of separation and angular divergence of the juxtaposed edges of the nib divisions and, in particular, of the ball portions 12, 12' thereof in the form of a wide inverted open-topped V for the widest writing line (see Fig. 6). Figs. 7 and 8 illustrate the relative position of ball sections 12, 12' as the nib divisions are compressed by the axial movement of the member carrying the pen point to attain respectively the medium and fine writing lines.

Pen point 10 is coaxially aligned and mounted within a tubular element generally indicated at 20, the heel 14 of the pen point being set and maintained against angular or rotary displacement relative to the ink channel to be later described, extending longitudinally in said tubular element, by semi-circular bushing 70 integral with the under part of feed plug 15, which is disposed in a bore 21 extending through element 20 and within a forward tubular extension 22 of element 20, the forward portion of the feed plug 15 being contoured to cooperate with the pen point, and the rear of which leads to the ink reservoir. The plug 15 has the usual upwardly sloping body portion 16 at its forward end and the usual channel 17 extending along its length. Element 20 has an intermediate enlargement 23 on which is formed a radial extension 24 of rectangular cross-section. Extension 24 carries two or more partial threads 25 for a purpose to be described. Rearwardly of enlargement 23, element 20 has a sleeve 26 secured thereon at a first reduced portion thereof, as by force fit.

Sleeve 26 has spot welded thereto one end of an elongated U-shaped spring 30 which longitudinally embraces the ink sac 31. The latter

has its open end secured over a reduced nipple or the like 27 on element 20, being held by a snap ring compressing the sleeve into an annular recess 28. The two arms 32, 33 of spring 30 are transversely curved to conform to the curvature and diameter of sac 31 when the latter is filled. The end of arm 33 is outwardly bent as at 34 to rest against barrel 35. Pressure of arms 32, 33 toward each other collapses sac 31 to expel air therefrom and release of the arms allows the sac to expand to draw ink thereinto. As substantially the entire length of the sac is collapsed, only one squeeze of spring 30 is needed to fill sac 31, and the ink intake is increased 40% compared to the usual pressure bar filling mechanism.

The rear end of element 20 is shaped to provide an angular configuration to its longitudinal axis, the lower elongated portion 18 thereof being arcuately sloped to define a spherical triangle, whereby as the ink supply becomes low, a maximum of ink passes from the ink reservoir onto the surface defined by the spherical angle for delivery to the channel 17 when the pen is held vertically.

The arcuate zones 90 of tapered edges 19, 19' of nib divisions 13, 13' of pen point 10 are embraced by the frusto-conical inner surface portion 40a of a cam sleeve 40 defining the hood. The slope of the inner frusto-conical portion 40a of hood 40 is greater than the taper of the edges 19, 19' of nibs 13, 13' so that, as pen point 10 is moved outwardly through sleeve or hood 40 by activation of element 20 by the rotation of control sleeve, as will be later described, the frusto-conical inner surface portion 40a of the hood or sleeve 40 engages the arcuate zones 90 of tapered edges 19, 19' of the nib divisions to press the same toward each other and to bring the juxtaposed ball portions 12, 12' into a relative position of less angular slope and transverse distance therebetween than the initial inverted V relationship thereof, the nib divisions and their ball portions expanding apart upon inward relative movement of pen point 10 and consequent release of pressure of the sleeve or hood 40. The arcuate zones 90 extend along tapered edges 19, 19' of the nib divisions 13, 13' for such distance that the angular and transverse displacement of the juxtaposed ball portions and the nib divisions adjacent thereto is effectuated, with that portion of the pen point at the pierce hole providing a fulcrum. Sleeve or hood 40, which is preferably of metal, has an inwardly extending tubular portion 41 engaging and acting as a bearing for extension 22 of element 20.

Sleeve or hood 40 fits tightly within an outer sleeve 42 whose peripheral surface forms a smooth continuation of that of the cam sleeve. Sleeve 42 has a recess 43 in its inner end receiving an extension 44 of a retainer member 45. The latter has a threaded inner end receiving the threaded outer end of a second retainer member 46 having an axially directed rectangular slot 47 in its outer end. Slot 47 slidably receives rectangular radial extension 24 of element 20, the relative depth of the wall of member 46 being substantially equal to the height of extension 24 so that the threads 25 project radially beyond member 46. The interengagement of extension 24 in slot 47 prevents rotation of element 20 while permitting axial movement of the latter, such axial movement being limited by engagement of either end of enlargement 23 with retaining member 45 or 46.

The outer surfaces of members 45 and 46 are

recessed to provide bearing seats for a selector sleeve 50 having internal teeth 51 meshing with teeth 25. Sleeve 50 is rotatable but cannot move axially, being restrained by the retaining members. Consequently, rotation of sleeve 50 effects axial movement of element 20, and its connected components, relative to cam sleeve 40 to adjust the width of the writing line.

Member 46 has an extension 48 which fits tightly within the inner end of barrel 35. The outer end of barrel 35 has fitted tightly therein a metal nipple 36 which extends beyond barrel 35 and is threaded to disengageably receive an elongated cap 37 enclosing spring 30 and sac 31. Cap 37 may be removed to operate spring 30 to fill sac 31.

The action of sleeve or hood 40 on pen point 10 is best illustrated by Figs. 6, 7 and 8. Fig. 6 illustrates the position of Fig. 1 in which sleeve or hood 40 is not in engagement with the tapered edges of pen point 50. In a typical embodiment, in this position, the separation of the upper ends of ball portions 12, 12' is 0.006" and that of the bottom ends is 0.008". In the intermediate position of Figs. 7 and 9, the upper separation is substantially zero and the lower separation is 0.002". In the "fine" line position of Figs. 2 and 8, the ball portions are substantially in full contact, the upper and lower separations approaching zero. Thus, by rotation of sleeve 50, the width of the writing line can be changed between the "broad" position of Fig. 5 and the "fine" position of Fig. 8. Suitable graduations can be provided on sleeve 50 and retainers 45 and/or 46 to facilitate the adjustment. It should be noted that pen point 10 is in the retracted position for "broad" writing, and in the extended position for "fine" writing. Only the outer end of sleeve or hood 40 provides the pressure zone for contact with the pen nib divisions.

While the cam surface defined at the forward end of the hood or sleeve 40 provides the mechanism for application or release of pressure against the longitudinally extending arcuate zones 90 of the tapered sidewalls 19, 19' of the nib divisions 13, 13', as the pen point is being axially displaced in opposing directions by the rotation of selector sleeve 50, the resultant pressure or release of pressure, as the directional axial movement of the pen point is varied, in addition to effectuating the desired change in the transverse spacing and the angular divergence along the slit of the juxtaposed nib divisions for producing the desired width of writing line, provides for a regulation of the ink flow along both the pen point slit and the ink channel below the pen point. On axial movement of the pen point outwardly to produce the finer writing line, the increase in pressure of the cam surface aforesaid against the nib divisions results in a downward and inward displacement thereof and a decrease in flow of ink, while axial movement inwardly causes a decreased pressure and permits the nib divisions to expand upwardly and outwardly to permit a greater flow of ink.

In order to provide egress of any ink which might be drawn into the nib adjusting sleeve when the pen is refilled, there is provided a drain groove extending longitudinally of the plug 15, such excess ink as it accumulates during filling passing around the pen point 10 within the confines of the frusto-conical inner surface of the nib adjuster until it reaches the groove along which it flows generally back to the ink reservoir.

While a particular embodiment of the invention has been shown and described in detail to

illustrate the application of the invention principles, it should be understood that the invention may be otherwise embodied without departing from such principles.

5 What is claimed is:

1. A writing pen, comprising a member having disposed at one end thereof a pen point longitudinally slit to provide juxtaposed nib divisions, a shell embracing said member and comprising a hood and a rotatable selector sleeve, operatively associated means on said member and said selector sleeve for axially displacing said member and the pen point carried thereon relative to said shell as said sleeve is rotated in either direction, said pen point being formed of resilient metal, the writing ends of the nib divisions being normally transversely and angularly spaced apart to form an inverted V, and means on said hood operatively associated with the nib divisions of said pen point for decreasing or permitting the increase of the transverse and angular spacing between the nib divisions of the pen point as said member is axially displaced, whereby to vary the width of the writing line of said pen point.
- 10 2. A writing pen, comprising a member having disposed at one end thereof a pen point longitudinally slit to provide juxtaposed nib divisions, the forward outer edges of which are tapered and of arcuate contour, a shell embracing said member and comprising a hood and a rotatable selector sleeve, operatively associated means on said member and said selector sleeve for axially displacing said member and the pen point carried thereon relative to said shell as said sleeve is rotated in either direction, said pen point being formed of resilient metal, the writing ends of the nib divisions being normally transversely and angularly spaced apart to form an inverted V, and means on said hood comprising
- 15 30 35 40 45 50 55 60 65 70 a portion having a frusto-conical surface of slope greater than that of the tapers of the edges of the nib divisions operatively associated with the nib divisions of said pen point for effectuating the application of pressure thereagainst by a cam action, thereby decreasing or permitting the increase of the transverse and angular spacing between the nib divisions of the pen point as said member is axially displaced, whereby to vary the width of the writing line of said pen point.
3. A fountain pen, comprising a member having an ink passage extending longitudinally thereof and having disposed at one end thereof a pen point of resilient material having an inverted V slit longitudinally therein to provide juxtaposed nib divisions and at the other end thereof an ink sac, a shell embracing said member and comprising a hood at one end, a barrel at the other end, and a rotatable selector sleeve intermediate said hood and barrel, operatively associated means on said member and said selector sleeve for axial movement of said member and the pen point carried thereon relative to said shell as said sleeve is rotated in either direction, and means on said hood operatively associated with the pen point for decreasing or permitting the increase of the slit between the nib divisions of the pen point as said member is axially displaced, whereby to vary the width of the writing line of said pen point.
4. A fountain pen, comprising a member having an ink passage extending longitudinally thereof and having disposed at one end thereof a pen point longitudinally slit to provide juxtaposed nib divisions and at the other end thereof an ink sac, a shell embracing said member and

comprising a hood at one end, a barrel at the other end, and a rotatable selector sleeve intermediate said hood and barrel, operatively associated means on said member and said selector sleeve for axially displacing said member and the pen point carried thereon relative to said shell as said sleeve is rotated in either direction, said pen point being formed of resilient metal, the writing ends of the nib divisions being normally transversely and angularly spaced apart to form an inverted V, and means on said hood operatively associated with the nib divisions of said pen point for decreasing or permitting the increase of the transverse and angular spacing between the nib divisions of the pen point as said member is axially displaced, whereby to vary the width of the writing line of said pen point.

5. A fountain pen, comprising a member having disposed at one end thereof a pen point longitudinally slit to provide juxtaposed nib divisions, a shell embracing said member and comprising a hood and a rotatable selector sleeve, operatively associated means on said member and said selector sleeve for axially displacing the member and the pen point carried thereon relative to said shell as said sleeve is rotated in either direction, said pen point being formed of resilient material, and means on said hood operatively associated with the nib divisions of said pen point for decreasing or permitting the increase of the separation of the nib divisions of the pen point as said

5
10
15

member is axially displaced, whereby to vary the width of the writing line of said pen point.

6. A fountain pen according to claim 5, wherein the member includes an ink passage element extending longitudinally thereof to the pen point and the hood is provided with a frusto-conical inner portion embracing said nib divisions to contact the same as said member is axially displaced, whereby to control the separation of the nib divisions and vary thereby the width of the writing line of said pen point and simultaneously therewith to displace the nib divisions toward and away from the ink passage element to control the supply of ink fed to the nib divisions in accordance with their degree of separation.
